UNITED STATES PATENT OFFICE.

WILLIAM H. BROWN, OF INDIANAPOLIS, INDIANA, ASSIGNOR TO HAUGH,
KETCHAM & CO., OF SAME PLACE.

LATHING AND FURRING.

SPECIFICATION forming part of Letters Patent No. 271,309, dated January 30, 1883.

Application filed June 23, 1882. (No model.)

To all whom it may concern:

Be it known that I, WILLIAM H. BROWN, of the city of Indianapolis, county of Marion, and State of Indiana, have invented certain new and useful Improvements in Lathing and Furring, of which the following is a specification.

My said invention consists in attaching T-shaped furring to the ordinary I-shaped flooring-beams of buildings by means of clips which engage with the flanges of said furring by means of a strap which passes under said clip and rests upon the lower flange of the I-beam, and a wedge, screw, or some other fastening device, by which the whole may be tightened up and made secure.

It further consists in attaching the lathing to the furring by cutting a transverse slot through the corrugations thereof, slipping said slot onto the lower edge of the furring, and inserting nails through holes in said furring beneath the upper corrugations.

Referring to the accompanying drawings, which are made a part hereof, and on which similar letters of reference indicate similar parts, Figure 1 is a section through a portion of a fire-proof floor, the under side whereof is covered by a system of lathing embodying my invention; Fig. 2, a similar section, on an enlarged scale, of that portion near the base of one of the I-beams only; and Fig. 3, a section taken transversely of the last.

In said drawings, the portions marked A represent the I-beams or floor-beams of a building; B, the T-shaped furring; C, the clips; D, the straps; E, the wedges; F, the lathing; G, the pins or nails for securing the same to the furring, and H the plastering.

The I-beams A are the ordinary iron floor-beams used in fire-proof buildings, and are shown in Fig. 1 as having the masonry arch between them which is commonly employed in floors of this character.

The furring B is composed of light T-shaped iron beams, which are provided with numerous small holes in their lower edges, through which to insert the nails or pins G. They are placed transversely of the beams A, and are secured thereto by my improved fastening devices.

The clips C are straps of iron bent around in the form best shown in Fig. 3, so that the points thereof shall engage under the flanges

of the beams B, and the loop portion shall extend above the feet of the beams A.

The straps D are straight or slightly-bent pieces of iron, which are inserted through the clips C, and one end of each of which rests upon the feet or lower flanges of the beams A.

The wedges E are adapted to be driven under the outer ends of the straps D, between them and the top surfaces of the beams B, and thus draw said straps, the clips, and said beams tightly up to the positions desired and hold them there securely. Instead of the wedge E, a screw, E', might be employed for this purpose; or the end of the strap might be turned over and act as the wedge; but I prefer the wedge as being more simple, less expensive, and more easily handled than the other devices.

The lathing F is simply the ordinary corrugated perforated sheet-iron lathing in common use, except that a slot, f, (see Fig. 3,) is cut across the corrugations, about half through from the top to the bottom of the same, into which the lower flange of the furring-beam B may enter.

The pins G may be any small pins, nails, or wire which will enter the holes in the lower edge of the beam B and hold the lathing thereto.

It will be readily seen that my improved fastening can be applied to any portion of the structure desired, as it will (when loose) freely slip in one direction on the beams A and in the other on the beams B, and be rigidly secured in any position at will. The method of securing the lathing is also simple, inexpensive, and easily practiced.

In so far as the furring and the method of fastening the lathing thereto are concerned, my invention is applicable to walls as well as ceilings. The furring can be secured to the walls in any suitable manner, and the lathing can be secured to the furring in the same way as that which has been described.

Having thus fully described my said invention, what I claim as new, and desire to secure by Letters Patent, is—

1. The combination, with the floor-beams of a building and furring consisting of light T-beams, of a fastening for securing them together, consisting of a clip, a strap, and a wedge or its equivalent, substantially as set forth.

2. The combination, with the furring B, of

the lathing F and the pin G, said lathing being slotted across its corrugations to admit the lower edge of the furring, and said furring being provided with holes to admit said pins, 5 substantially as set forth.

3. The combination of the floor-beams A, furring B, clips C, straps D, wedges or equivalent parts E, lathing F, and pins G, substantially as described, and for the purposes specified.

In witness whereof I have hereunto set my hand and seal, at Indianapolis, Indiana, this 20th day of June, A. D. 1882.

WILLIAM H. BROWN. [L. S.]

In presence of—

C. BRADFORD,
E. W. BRADFORD.
